UNITED STATES PATENT OFFICE.

JOHN LYNDALE, OF MINNEAPOLIS, MINNESOTA.

AUTOMATICALLY-CONTROLLED UNIVERSAL JOINT FOR ARTIFICIAL LEGS.

Application filed March 29, 1924. Serial No. 702,837.

To all whom it may concern:

Be it known that I, JOHN LYNDALE, a citizen of the United States, residing at Minneapolis, in the county of Hennepin and State of Minnesota, have invented certain new and useful Improvements in Automatically-Controlled Universal Joints for Artificial Legs; and I do hereby declare the following to be a full, clear, and exact description of the invention, such as will enable others skilled in the art to which it appertains to make and use the same.

My invention relates to artificial legs and has for its object to improve the foot action as will hereinafter appear.

To the above end, generally stated, the invention consists of the novel devices and combinations of devices hereinafter described and defined in the claims.

20 In the accompanying drawings, which illustrate the invention, like characters indicate like parts throughout the several views.

Referring to the drawings:

Fig. 1 is a side elevation of an artificial leg having my invention embodied therein and applied to a leg having the amputation below the knee;

Fig. 2 is a view partly in front elevation and partly in transverse vertical section 30 taken on the line 2—2 of Fig. 1;

Fig. 3 is a detail view of the ankle joint, with some parts sectioned on the line 3—3 of Fig. 2, on an enlarged scale; and

Fig. 4 is a detail view with some parts 35 sectioned on the line 4—4 of Fig. 1.

The artificial leg illustrated is for an amputation below the knee, and of the parts thereof, it is important to note the foot section 5, shank or lower leg section 6, upper leg section 7, side knee joints 8 formed by pivotally connected upper and lower metal straps 9 and 10, respectively, and which straps 9 and 10 are secured to the upper leg section 7 and lower leg section 6, respectively.

The parts thus far described are of standard and well known construction.

50 My improved ankle joint includes a transverse bearing sleeve 11 and a longitudinal bearing sleeve 12 located, the former above the latter, and which bearing sleeves are rigidly connected in cross relation. The transverse bearing sleeve 11 is turnably mounted in open half seats 13 in the lower leg section 6, and the longitudinal bearing sleeve 12 is turnably mounted in open half

seats 14 in the foot section 5. Each bearing sleeve 11 and 12 is provided with a pair of axially spaced circumferential flanges 15 that hold said bearing sleeves against axial movement. The bearing sleeve 11 is held in its seat by a nut-equipped T-bolt anchored to a transverse bar 17 in the lower leg section 6. The head of this T-bolt 16 is mounted in the bearing sleeve 11 and on which head 65 said bearing sleeve is free to turn.

A circumferential slot 18 is formed in the bearing sleeve 11 for the body of the bolt 16, and which slot permits the required rotation of said bearing sleeve on the head of the bolt 16. This body of the T-bolt 16 is separably connected to the head thereof by screw threads to permit said head to be inserted axially into the bearing sleeve 11 and then attached to the body of the T- 75 bolt.

The longitudinal bearing sleeve 12 is held in its half seat 14 by a T-bolt 19 in the same manner that the bearing sleeve 11 is held in its seat, and the body of this bolt extends through a circumferential slot 20 in the bearing sleeve 12. Said T-bolt 19 is anchored in the foot section 5 and said foot section is recessed at its under side to receive the nut of said bolt. Obviously, by adjusting the nuts on the T-bolts 16 and 19, the operative length of said bolts may be varied at will to properly hold the respective bearing sleeves in their seats. Obviously, the transverse bearing sleeve 11 permits the required rocking movement about the transverse axis of the foot section 5 in respect to the lower leg section 6 and the longitudinal bearing sleeve 12 permits a rocking movement about the longitudinal axis of said foot section 5. The sides of the foot section 5 are notched at 21 to afford clearance for the transverse bearing sleeve 11 to permit the required rocking movement of the foot section 5. 90 95 100

To hold the foot section 5 against a rocking movement about the transverse axis when the upper leg section 7 is in an upright position, or in other words when the wearer of the artificial leg is standing up, I provide a tension strap 22 having at its ends heads 23 that are pivoted at 24 to the hinged straps 9, and which pivot point is eccentric to the hinge joint 8 and thereby imparts a crank movement to the tension strap. The end portions of the tension strap 22 are inserted through apertures 25 in the 105 110

sides of the lower leg section 6, and from thence they extend downward through the open lower end of said lower leg section and along the sides of the foot section 5, back of the ankle joint. The intermediate portion of the tension strap 22 extends through a transverse slot 26 formed in the heel of the foot section 5 and is free to permit the required rocking movement about the longitudinal axis of said foot section on the bearing sleeve 12.

To permit the tension strap 22 to be longitudinally adjusted, the same is made in two sections, and one of said sections is provided with a loop 27 through which the other strap section is looped and then secured by a buckle 28. The length of the tension strap 22 is such that when the upper leg section 7 is in an upright position, the heel portion of the foot section 5 is held in engagement with the lower leg section 6 to hold the foot section 5 against rocking movement about a transverse axis.

When the upper leg section 7 is in a horizontal position, or in other words when the wearer of the artificial leg is sitting down, the tension strap is slack, due to the crank movement of the connected ends of said strap with the hinge straps 9, and thereby permits free rocking movement about the transverse axis of the foot section 5 in respect to the lower leg section 6. In all positions of the upper leg section 7, the foot section 5 is free to rock about the longitudinal axis for the reason that the same is free to slide on the tension strap 22.

By providing the ankle joint with the longitudinal bearing sleeve 12, the foot section is free to rock about the longitudinal axis at all times, thus making it easier for the wearer of the artificial leg, especially on uneven surfaces, as it gives the foot section 5 a natural movement. When the wearer is walking, the tension strap 22 securely holds the foot section 5 from swinging on the transverse bearing sleeve 11. When the wearer is sitting down, there is sufficient slack in the tension strap 22 to permit the foot section 5 to freely move about the transverse bearing sleeve 11 so that the foot section 5 may be held in a natural position even when it is drawn backward or moved forward.

The above described invention has been in actual use on an artificial leg worn by the inventor and has proven highly efficient for the purpose had in view. He has found

that he can walk in a much more natural way and with less effort, and particularly so on rough and uneven ground as the foot section 5 is free to rock about the longitudinal axis.

What I claim is:

1. In an artificial leg, the combination with upper and lower leg sections connected by a knee joint, a foot section and an ankle joint connecting the foot section to the lower leg section for free pivotal movements both longitudinally and transversely, of a foot tension strap anchored to the upper leg section for crank-acting movement in respect to the knee joint and extending transversely loosely through the foot section back of the ankle joint and arranged to hold the foot section against rocking movement about a transverse axis when the upper leg section is in an upright position and to release said foot section for free pivotal movement when the upper leg section is in a horizontal position, said tension strap permitting free rocking movement about a longitudinal axis of the foot section at all times.

2. In an artificial leg, the combination with upper and lower leg sections connected by a knee joint, a foot section and an ankle joint connecting the foot section to the lower leg section for pivotal movements both longitudinally and transversely, of a foot tension strap having its ends anchored to the upper leg section for crank-acting movement in respect to the knee joint, the intermediate portion of said tension strap being extended transversely loosely through the foot section back of the ankle joint and arranged to hold the foot section against rocking movement about a transverse axis when the upper leg section is in an upright position and for releasing the foot section when the upper leg section is in a horizontal position.

3. The structure defined in claim 2 in which said tension strap is longitudinally adjustable.

4. The structure defined in claim 2 in which the end sections of the tension strap are extended upward through the interior of the lower end portion of the lower leg section and outward through apertures in the sides thereof.

In testimony whereof I affix my signature.

JOHN LYNDALE.
